Henry Cox of Philadelphia Penn.
Letter's Patent No. 2476. Dated Oct. 2, 1804
Design for a Dentist's Grinding Slathe.

The Schedule referred to in this Letters Patent, and making part of the same.

To all whom it may concern:

I, Henry Cox of the City of Philadelphia in the State of Pennsylvania have invented or produced a new and original Design for a Dentist's Grinding Slathe, of which the following is a full, clear, and exact description reference being had to the accompanying drawing, making a part of this Specification, and to the letters of reference marked theron.

A, is a wheel having a rim with a flat inner periphery α' , a hub α^3 , and four outward curved spokes or arms $\alpha^1, \alpha^2, \alpha^3, \alpha^4$, all formed as shown. B, is a support having projections b^1, b^2 , thumb screw b^2 , and standards b^3, b^4 , formed as shown. C, is a smaller wheel in a mandrel c^1 , having screw chucks c^2, c^3 . All of the said parts are formed and arranged in relation to each other as shown.

What I claim as my invention and desire to secure by Letters Patent is
The Design hereinafter set forth, for a Dentist's Grinding Slathe.

Witnessed

Benj. Morrison.
